OVERHEAD DOOR CONSTRUCTION

Alvin V. Rowe, Galesburg, Ill., assignor to Rowe
Manufacturing Company, Galesburg, Ill., a cor-
poration of Illinois

Application November 30, 1938, Serial No. 243,245

8 Claims. (Cl. 20—20)

This invention relates generally to overhead door constructions but more particularly to overhead door constructions in which the door panel or panels are adapted laterally to be moved into sealing relation with respect to a door opening after reaching a closing position.

In the design of overhead door constructions, efforts have been made to reduce as far as possible frictional resistance as the door panels are shifted between open and closed positions. To this end it has been common practice to employ guide rollers equipped with ball bearings, and counterbalancing springs have been used to facilitate the ease with which the door may be operated.

Various mechanisms have been offered whereby to effect the automatic sealing of the door panels with respect to the door opening as said panels approach their door-closing position. In all of these devices with which I am familiar, increased frictional resistance to door movements is developed as the door panels approach their downward or door-closing position. Thus, for example, in certain installations tapered or inclined guide tracks are employed which cause the front marginal portions of the door panels to be carried into frictional engagement with the complementary inner surfaces of the door frames during the last several inches of travel of the panels. In other words, during the latter portion of this downward movement, friction is established between the door panels and the door frames. This not only increases the force required to ultimately close the door panels, but also increases the force necessary to initially shift the panels from their closed toward their open position. Also such installations are affected by changes in climatic conditions because such conditions cause the door panels to experience expansion and contraction. Expansion of the door panels obviously increases the period of frictional engagement between the panels and the door frames. In other installations with which I am familiar, wherein the lateral sealing movement of the door panel occurs as an incident to the downward movement of said panels, a period of frictional engagement takes place before said panels reach their limiting downward or door-closing position.

It is, therefore, one of the primary objects of the present invention to obviate the disadvantages and inconveniences presented by the above mentioned and other conventional overhead door constructions and to this end I propose to preclude the establishment of any frictional resist-

ance between the door panels and frame structures before said panels reach their ultimate, downward door-closing position. That is to say, the present invention contemplates the provision of means whereby the sealing relation of the door panels with respect to the door opening is established after vertical downward movement of the door panels has been completed.

It is a further object of the present invention to release the sealing pressure of the door panels and side frames before said panels experience any upward movement, thereby avoiding the necessity of overcoming this sealing pressure when the panels are initially shifted upwardly from their door-closing position.

More specifically, the invention contemplates the provision, in combination with an overhead door construction of the general type and class referred to above, of sealing and releasing means which may be manually manipulated with little effort and from a convenient position intermediate the sides of the door panels.

Another object of the present invention is to provide manually operable door-sealing means which may be controlled by manual manipulation of the locking lever which is usually located centrally with respect to the door panels, and which may be operated either from the outside or the inside of the door panels.

Still more specifically, the invention contemplates the provision of control means for causing and releasing sealing pressure which will operate simultaneously on all door panels along the oppositely disposed, vertical margins of the door panels when in closed position.

The foregoing and numerous other objects and advantages will be more apparent from the following detailed description when considered in connection with the accompanying drawings wherein:

Figure 1 is an inside elevational view of an overhead door construction constructed in accordance with the teachings of the present invention, said view constituting a vertical section taken substantially along the line 1—1 of Figure 5;

Figure 2 is an enlarged elevational view of the portion of the track structure and associated elements included within the bracket designated by the numeral 2 in Figure 1;

Figure 3 is a side elevational view of the device as viewed from the right of Figure 2, a portion of the track structure being broken away to more clearly illustrate the structural characteristics

of the vertically shiftable cam actuating member;

Figure 4 is a sectional view taken substantially along the line 4-4 of Figure 3 to more clearly illustrate the manner in which the track structure oppositely disposed from the cam member is released to permit lateral movement of the guide roller and the consequent establishment of sealing pressure between the complementary door panel and door jamb;

Figure 5 is an enlarged vertical sectional view taken substantially along the line 5-5 of Figure 1, disclosing in elevation one of the track structures embodying the panel-sealing mechanism contemplated by the present invention;

Figure 6 is an elevational view of the cam members and actuating means therefor disassociated from the upright track structure;

Figure 7 is an enlarged fragmentary elevational view of the portion of the section included within the bracket designated by the numeral 7 in Figure 5;

Figure 8 is an elevational view of the structure as viewed from the right of Figure 7;

Figure 9 is an elevational view as viewed from the left of Figure 8 along the line 9-9 of Figure 8, with a portion of said parts shown in section to more clearly illustrate the manner in which the vertically shiftable cam supporting element is coupled with the bell crank device of Figure 8;

Figure 10 is an enlarged vertical transverse sectional view taken across the upright track section substantially along the line 10-10 of Figure 8;

Figure 11 is an enlarged fragmentary side elevational view of the upper half of the upright track section of Figure 5, with a portion thereof broken away to disclose the structural arrangement of parts otherwise hidden;

Figure 12 is a fragmentary elevational view taken from the right of Figure 11;

Figure 13 is a fragmentary horizontal sectional view taken substantially along the line 13-13 of Figure 11;

Figure 14 is a horizontal transverse sectional view taken substantially along the line 14-14 of Figure 11;

Figure 15 is a perspective view of one of the cam elements detached from its supporting or actuating member;

Figure 16 is a perspective view of the cam actuating member and cam supported thereby employed to effect lateral door-sealing movement of the door panels shown in Figures 11 and 12;

Figure 17 is a fragmentary perspective view of a section of the upright track which is cooperatively associated with the cam actuating member of Figure 16; and

Figure 18 is a fragmentary perspective view of the lower cam actuating member and means for coupling said member to the upper cam actuating member disclosed in Figure 16.

Referring now to the drawings more in detail wherein like numerals have been employed to designate similar parts throughout the various figures, it will be seen that, for the purpose of illustrating one practical embodiment of the invention, the same is disclosed in association with a door structure designated generally by the numeral 20, which includes a plurality of door panels 22, 24, 26, and 28, which are adapted to be shifted between vertical door closing position and horizontal overhead opened position

along a pair of identical oppositely disposed guide rails or tracks indicated generally by the numeral 30. Each of the tracks 30 includes an upright or vertically disposed track section 32, a curved section 34, and a horizontal section 36.

The three lowermost door panels are connected in edge-to-edge relation along their outer margins by identical hinge means designated generally by the numeral 38, whereas the two uppermost panels are connected at their opposite margins by identical hinge means designated generally by the numeral 40. Each of the hinge means 38 includes a pintle 42, which carries a guide roller 44. The detailed arrangement of the hinge means 40 and the guide roller 46 carried thereby will be more apparent from the description which is to follow. It will suffice at this point in the description to say that the door panels 22, 24, 26, and 28 are adapted to be shifted between the closed vertical position shown in the various figures to an open overhead position through the agency of the guide rollers 44, 46, and guide rollers 48 which travel within the tracks or rails 30.

It will be observed that each vertical track section 32 includes a flat guide portion 50 adapted to be secured to a complementary door jam 52, and the oppositely disposed guide portion of the track section 32 is curved to receive the curved periphery of the guide rollers. It will be apparent that, as the door panels are shifted from their open overhead position to the limit of their door closing position, no lateral movement of the door panels into sealing engagement with the door jams 52 takes place automatically. In other words, the track section is disposed in parallelism with the door jamb and no means is provided which operates as an incident to the closing movement of the door panels for effecting automatically lateral movement of the door panels into frictional engagement with the inner surface of the door jams 52. As a result, the force required to move the door panels downwardly, as said panels approach the limit of their closing position, is not counteracted by frictional resistance between the door panels and door jams, as in conventional installations with which I am familiar.

The present invention contemplates means for effecting lateral movement of the door panels into sealing engagement with the door jams after the panels reach their fully closed or downward position. This door sealing means includes actuating mechanism designated generally by the numeral 54, which is cooperatively disposed with respect to and, in fact, actuated by a complementary lock bar 56 (Figures 1, 7, and 8). Each of the lock bars 56 is reciprocably mounted at its free extremity within brackets 58 marginally secured to the door panel 24. Each of the lock bars 56 is continuously urged inwardly toward each other through the agency of a spring element 60. The inner extremities of the lock bars 56 are pivotally connected with a control handle mechanism 62, which is mounted centrally of the panel 24 in a convenient position for manual manipulation. The mechanism 62 includes a handle member 64 which may be rotated so as to longitudinally shift the bars 56 when a latch member 66 of a lock mechanism 68 is withdrawn from a complementary peripheral recess in the mechanism 62. This lock mechanism 68 functions in accordance with conventional locking devices for overhead doors, and hence a further detailed description

tion thereof is not necessary for a clear understanding of the present invention.

Referring now to the actuating mechanism 54 (Figures 7 and 8), it will be seen that one arm 70 of a bell crank mechanism carries a roller 72 which is adapted to be engaged by the free extremity of the lock bar 56. The arm 70 is pivotally mounted at 74, which pivot also supports a companion bell crank arm 76. The arms 70 and 76 are resiliently coupled through the agency of a coil spring 78. The free extremity of the arm 76 makes a slot-and-pin connection with a vertically disposed actuating bar 80. It will be also noted that the actuating mechanism 54 including the bell crank arms 70 and 76 is mounted upon a bracket or frame 82 adjustably secured by suitable means, such as nuts 84, to the side of the vertical track section 32. Movement of the lock bar 56 (Figure 8) to the left in engagement with the roller 72 causes the vertical actuating bar 80 to be shifted upwardly so as to effect simultaneous lateral movement of the door panels into sealing engagement with the door jambs 52 in the manner about to be described.

It will be noted that the vertical actuating bar 80 is preferably curved so as to fit into the complementary curvature of the vertical section 32 of the guide track 30 (see Figure 10). The foregoing slot and pin connection comprises a pin 86, which cooperates with a slot 88 in the bell crank arm 76, is secured to the vertical actuating member 80, and is also secured to a block 90, which superimposes the member 80 and is vertically shiftable within a complementary slot 92 formed in the track section 30. A plate 94 (Figure 10) superimposes the block 90 and extends on opposite sides beyond the slot 92. With this arrangement, the actuating member 80 is guided in its vertical reciprocation. It will be noted that the plate 92 is secured to the actuating bar 80 and the block 90 by suitable screws 96.

The actuating bar or member 80 carries a plurality of cam members or elements 98, the lowermost cam member 98 being companion to the lowermost door panel 22, the intermediate cam members 98 being companion to the door panels 24 and 26, and the upper cam member being companion to the door panel 28. These cam members are all similar in their function, and hence the disclosure of one will serve as a disclosure of all. By referring to Figures 2 to 4, inclusive, a clear understanding of the structure and function of these cam members will be obtained. It will be noted that the cam member 98 is adjustably secured to the actuating bar 80 through the agency of a screw 100 which extends through a slot 102 in the actuating bar 80. A washer 104 is of sufficient width to span a slot 106 in the track section 32, through which the cam member 98 extends and in which said cam member is vertically reciprocable. It will also be noted that each of the cam elements 98 is positioned in the vicinity of the complementary guide rollers 44 and, as upward movement is experienced by the actuating bar in response to the outward shifting of the lock bars 56, the inclined surfaces 108 of the cam members 98 engage the material of the track at the upper extremity of the slots 106, thereby causing the actuating bar to shift laterally toward the door jambs 52. The complementary rollers 44 engaging the inner curved surface of the bar, are simultaneously moved so as to carry the periphery of the roller through a slot or recess 110 provided in the flat tread portion 50 of the track section 32. This movement of the rollers 44 causes the door

panels 22, 24, and 26 to be shifted into tight sealing engagement along their oppositely disposed marginal surfaces with the complementary surface portions of the door jambs 52. This sealing or clamping engagement of the door panels with respect to the door jambs occurs as the periphery of the rollers 44 moves into the complementary slots or recesses 110. From the foregoing it will be apparent that, as a result of the upward movement of the actuating bar 80, the door panels 22, 24, and 26 are simultaneously shifted into sealing relation with respect to the door opening which is defined by the door jambs 52.

In addition to the actuating member 80 and the cam members 98 associated therewith, I employ an upper actuating section or bar designated by the numeral 80a, which also carries cam members 98a. This upper section 80a is particularly designed to effect the sealing or clamping engagement of the upper door panel 28 with respect to the door jambs, 52, and the structural features of this portion of the actuating mechanism are best disclosed in Figures 11 to 18, inclusive. The vertical actuating bar or member 80, previously described, is reciprocable within the curved portion of the vertical track section 32, whereas the vertical actuating member or section 80a is reciprocable along the outer surface of the curved portion of said track section. The lower portion of the U-shaped actuating member 80a is provided with a slot 112 which serves to permit adjustable coupling of the member 80a with the member 80. This coupling includes a guide block 114 which is vertically reciprocable within a complementary recess or slot 116 provided in the curved portion of the track section 32, and a screw 118, which serves to clamp together the upper extremity of the bar 80 and the lower extremity of the bar 80a. The upper extremity of the bar 80 reciprocably interlocks with and is guided by a slot 120 provided in the track section 32 (Figures 11 and 14). It will be seen that a section 122 of the bar 80a is bent inwardly so as to project through the guide slot 120. From the foregoing it will be apparent that vertical movement of the actuating bar 80 also causes vertical movement of the bar 80a and the cam members 98a supported thereby.

The lowermost cam member 98a is adjustably secured to the bar 80a by means of a screw 124, which extends through a complementary slot 126. The two uppermost cam members 98a are likewise adjustably secured by screws 128, which extend through complementary slots or recesses 130. As the cam members 98 move upwardly, the lowermost cam member engages a roller 132 and the two uppermost spaced cam members engage complementary rollers 134. The roller 132 (see Figures 11 and 13) is carried by a bracket 136 which is pivotally mounted upon the pintle 138 of the hinge 40. Disposed on the opposite side of the pintle 138 and carried by the frame or bracket 136 is the guide roller 46. Thus, as the roller 132 is swung upwardly to the right (Figure 11), the guide roller 46 is swung downwardly and to the right into engagement with the inner curved portion of the track section 32. This causes the pintle 138 to experience lateral movement to the left, thereby causing the upper portion of the panel 26 and the lower portion of the panel 28 to be moved into clamping engagement with the complementary portion of the door jambs 52. A spring 140 serves to continuously urge the roller 132 into engagement with its complementary cam 98a.

The structure supporting the roller 134 is identical with the structure supporting the roller 132, and hence detailed description thereof is not essential. It will be noted that the rollers 134 operate with the guide roller 48 in causing the clamping engagement of the upper portion of the door panel 28 with the door jamb 52. A pintle 142 supported by a bracket 144 serves the same purpose as the pintle 138 previously described.

By employing the rollers 134, together with their pivotal supporting brackets, the uppermost panel may move between vertical door closing position and open overhead position along the curved section 34 of the track without any interference or binding. By having the cam members 98a positioned externally of the track, as distinguished from the cam members 98 which extend from within the track, the ease with which the uppermost panels of the door structure may be shifted is materially enhanced. This arrangement avoids the necessity of providing recesses or slots in the flat tread portion 50 in the upper vicinity of the vertical track section 32. Hence the ease of operation, as well as the elimination of noise, results.

Referring again to the springs 78 disclosed in Figures 7 and 8, attention is directed to the fact that these springs continuously urge the bell crank arm 76 in a counterclockwise direction, as viewed in Figure 8. Thus, after the door panels have been shifted and clamped in their closed vertical position, any lateral vibration experienced by the door panels will cause the spring 78 to function in such a manner as to effect a firmer or tighter engagement of the panels with the door jambs. In other words, lateral vibration of the door panels enables the springs 78 to urge the actuating bars 80 in an upward direction, and thus effect a tighter sealing engagement of the panels with the door jambs. Thus springs or yieldable members 78 serve to automatically increase the clamping effectiveness of the door structure when vibrations are experienced thereby after they have reached their lowermost door closing position.

From the foregoing it will be apparent that my invention contemplates an improved overhead door construction, wherein frictional engagement between the door panels and door jamb structure during vertical travel of the door panels is eliminated. Hence, it avoids the necessity of using slanting tracks, rollers spaced at different distances from the door jamb, as well as wedge members of any kind. In fact, the use of any mechanism for building up frictional resistance between the door panels and door jambs during the final door closing movement or the initial door opening movement is completely eliminated when the present invention is employed. The overhead door structure contemplated hereby may be economically produced and installed. Also, the means for automatically increasing the sealing or clamping effectiveness of the door panels, when lateral vibration is experienced thereby, materially increases its operative efficiency.

While certain specific embodiments have been disclosed herein, it will be apparent that the invention is not limited thereto, but contemplates various modifications and changes without departing from the spirit and scope of the appended claims.

Having thus described my invention, what I claim as new and desire to secure by Letters Patent is:

1. In an overhead door construction, a pair of guide tracks, each track comprising a fixed vertical section adapted to be positioned adjacent the inner surface of a door frame defining a door opening, a horizontal overhead section, and a curved section intermediate said vertical and horizontal sections, a plurality of hingedly connected door panels slidably mounted upon said tracks and adapted to be shifted thereon between door-closing vertical position and open overhead position, and shiftable means for simultaneously moving said panels at vertically spaced positions in a lateral direction only into sealing relation with respect to the door opening after the door panels have reached their lowermost position closing the door opening.

2. In an overhead door construction, a pair of guide tracks, each track comprising a fixed vertical section adapted to be positioned adjacent the inner surface of a door frame defining a door opening, a horizontal overhead section, and a curved section intermediate said vertical and horizontal sections, a plurality of hingedly connected door panels slidably mounted upon said tracks and adapted to be shifted thereon between door-closing vertical position and open overhead position, and shiftable means manually controllable from a position intermediate the sides of the door panels for simultaneously moving said panels at vertically spaced positions in a lateral direction only into sealing relation with respect to the door opening after the door panels have reached their lowermost position closing the door opening.

3. In an overhead door construction, a pair of guide tracks, each track comprising a fixed vertical section adapted to be positioned adjacent the inner surface of a door frame defining a door opening, a horizontal overhead section, and a curved section intermediate said vertical and horizontal sections, a plurality of hingedly connected door panels slidably mounted upon said tracks and adapted to be shifted thereon between door-closing vertical position and open overhead position, said door panels having vertically spaced members adapted to be engaged for laterally shifting the door panels when they occupy their lowermost door-closing position, and shiftable means for simultaneously engaging said vertically spaced members to shift said panels in a lateral direction into sealing relation with respect to the door opening after the door panels have reached their lowermost position closing the door opening.

4. In an overhead door construction, a pair of guide tracks, each track comprising a fixed vertical section adapted to be positioned adjacent the inner surface of a door frame defining a door opening, a horizontal overhead section, and a curved section intermediate said vertical and horizontal sections, a plurality of hingedly connected door panels slidably mounted upon said tracks and adapted to be shifted thereon between door-closing vertical position and open overhead position, and shiftable means for simultaneously moving said panels at vertically spaced positions in a lateral direction into sealing relation with respect to the door opening after the door panels have reached their lowermost position closing the door opening, said shiftable means including a yieldable member for automatically increasing the sealing effectiveness of the door panels when vibrations are experienced thereby after said panels have reached their aforesaid lowermost position.

5. In an overhead door construction, a pair of 5
guide tracks, each track comprising a fixed vertical
section adapted to be positioned adjacent the
inner surface of a door frame defining a door
opening, a horizontal overhead section, and a
curved section intermediate said vertical and
horizontal sections, a plurality of hingedly con-
nected door panels slidably mounted upon said
tracks and adapted to be shifted thereon be-
10 tween door-closing vertical position and open
overhead position, and shiftable means includ-
ing actuating members shiftable upon said vertical
track sections for simultaneously moving said
panels at vertically spaced positions in a lateral
15 direction into sealing relation with respect to the
door opening after the door panels have reached
their lowermost position closing the door opening.
6. In an overhead door construction, a pair of 20
guide tracks, each track comprising a fixed vertical
section adapted to be positioned adjacent the
inner surface of a door frame defining a door
opening, a horizontal overhead section, and a
curved section intermediate said vertical and
25 horizontal sections, a plurality of hingedly con-
nected door panels carrying guiding members
slidably mounted upon said tracks and adapted to
be shifted thereon between door-closing vertical
position and open overhead position, and shiftable
30 means adapted to engage the structure of said
guiding members for simultaneously moving said
panels at vertically spaced positions in a lateral
direction into sealing relation with respect to the
door opening after the door panels have
35 reached their lowermost position closing the door
opening.

7. In an overhead door construction, a pair of
guide tracks, each track comprising a fixed vertical
section adapted to be positioned adjacent the

inner surface of a door frame defining a door
opening, a horizontal overhead section, and a
curved section intermediate said vertical and
horizontal sections, a plurality of hingedly con-
nected door panels carrying guide rollers mounted
upon said tracks and adapted to be shifted there-
on between door-closing vertical position and
open overhead position, and shiftable means
adapted to engage said guide rollers for simulta-
neously moving said panels at vertically spaced 10
positions in a lateral direction into sealing rela-
tion with respect to the door opening after the
door panels have reached their lowermost posi-
tion closing the door opening.

8. In an overhead door construction, a pair of 15
guide tracks, each guide track comprising a fixed
vertical section adapted to be positioned adjacent
the inner surface of a door frame defining a door
opening, a horizontal overhead section, and a
curved section intermediate said vertical and 20
horizontal sections, a plurality of hingedly con-
nected door panels, a guide roller carried by the
hinges of said door panels and mounted upon said
tracks to facilitate shifting said door panels on
said tracks between door closing vertical posi- 25
tion and open overhead position, shiftable actu-
ating members associated with the vertical sec-
tion of each track adapted to engage the struc-
ture of said guide rollers for simultaneously mov-
ing said panels at vertically spaced positions in 30
a lateral direction into sealing relation with re-
spect to the door opening after the door panels
have reached their lowermost position closing the
door opening, and a manually operable control
member for causing movement of said actuator 35
member after the door panels have reached their
aforesaid lowermost position.

ALVIN V. ROWE.
